UNITED STATES PATENT OFFICE.

FRANK E. FIELD, OF SOMERVILLE, NEW JERSEY, ASSIGNOR TO WESTERN ELECTRIC COMPANY, INCORPORATED, OF NEW YORK, N. Y., A CORPORATION OF NEW YORK.

ELECTROMAGNETIC DEVICE.

Application filed December 28, 1921. Serial No. 525,504.

This invention relates to electromagnetic devices, and particularly to means for controlling the resonance frequency of such devices.

5 It is an object of the invention to provide means for adjusting the resonance frequency of electromagnets.

It is well known that an electromagnet or coil having a certain inductance will resonate with its internal capacity at a definite frequency. However, it is frequently desired to raise this resonance point to a higher frequency without destroying the good qualities of the coil. In accordance with a 15 feature of the invention the resonance frequency of such a coil is changed to some predetermined higher point by inserting in the core of the coil a sheet or lamination of some good electrical conductor, such as copper. 20 By a proper insertion of such laminations the leakage of the coil may be controlled.

Other objects and advantages of the invention will be set forth in detail in the following description, and particularly 25 pointed out in the appended claim.

In the drawing, Fig. 1 shows the invention as applied to a simple transformer, and Fig. 2 shows the invention embodied in a rectangular core, certain parts being broken 30 away to more clearly illustrate the invention.

Referring to the drawing, Fig. 1 shows a transformer in which a core 3, comprising a plurality of laminations of magnetic material, is wound in the usual manner with 35 superimposed layers of a conductor 4. A plurality of laminations of copper 5 are inserted in the core for the purpose of raising its resonance frequency. At low frequencies the eddy current loss in these sheets will 40 not be appreciable, but as the frequency goes up the loss increases as the square of the frequency. These eddy currents act upon the core and crowd out some of the flux, thus decreasing the inductance of the coil and 45 raising its resonance frequency, since the ca-

pacity is fixed. The resonance frequency of the coil may be raised to a still higher value by increasing the number of sheets of copper in the core. It will be seen that by varying the thickness of the copper or by increasing the number of such laminations it is possible to control the resonance frequency of the coil. By properly computing the value of the non-magnetic conductor inserted in this manner it is possible to control the amount of leakage of a coil. In Fig. 2 the same arrangement is employed except that the coil 6 is provided with an external rectangular laminated core 7. These laminations are held in place by a screw 8 at each corner of the core or by any clamping means well understood in the art. This core is readily assembled and it is simply necessary to loosen the clamping screws 8 in order to replace some of the magnetic laminations 60 with laminations of non-magnetic conducting material, such as is shown at 9. It is to be understood that the invention is not limited to the specific construction herein shown, and described except as defined by 65 the scope of the following claim.

What is claimed is:

An electromagnetic device comprising a winding having effective capacity in shunt thereto and a core for said winding, said core being made up of laminations of magnetic material and laminations of electrically conducting non-magnetic material, the number and thickness of the magnetic and non-magnetic laminations being relatively proportioned with reference to a resonance frequency which the device is desired to possess whereby the effective inductance of the device is controlled to resonate with the said effective shunt capacity at the said resonance frequency.

In witness whereof, I hereunto subscribe my name this 20th day of December A. D., 1921.

FRANK E. FIELD,
